UNITED STATES PATENT OFFICE

2,536,229

ELECTRIC CRUCIBLE

Fernand Salvador, Marseille, France

Application August 30, 1948, Serial No. 46,842
In France September 12, 1947

1 Claim. (Cl. 13—21)

1

The present invention has for object an electric crucible for rapidly reaching temperatures of 900° C. and above, and particularly for melting soft metals and other materials.

To obtain this result, the crucible according to the invention concentrates the maximum of calories at the interior of the crucible, that is to say on the material to be treated, by disposing the heating elements at the interior, that is to say in direct contact with the said material. These heating elements, of appropriate number, are disposed along interior generatrices of the lateral cylindrical wall of the crucible in projecting portions of the wall which penetrate into the material to be treated, thus assuring a maximum heat-exchange surface.

The invention is shown by way of example in the accompanying drawing, wherein:

Fig. 1 shows a central vertical section.

Fig. 2 shows a plan view.

To obtain a thermal conductivity which is great as possible, the heating elements, which are long and of cylindrical or like form, are lodged in interior projections 2 of the lateral wall 5 of a crucible 1 having a base 3, these projections being hollowed axially from top to bottom to form cavities 4 for the heating elements (not shown). Thus the casing of each heating element can fit snugly to the wall of the crucible. The hollowed cavities 4 are readily accessible through the lower part of the crucible.

Each heating element is formed of a tube of refractory material which contains resistances of high resistivity. All the heating elements are readily interchangeable, being slidable in their cavities 4. In order to protect the resistances against oxidisation they are embedded in magnesia which prevents any contact with the air.

All the resistances or heating elements are retained in a quasi-vertical position by appropriate means, and are suitably connected up electrically.

The crucible is surrounded with heat insulation (not shown) which is in turn protected by an exterior casing, (not shown).

The crucible is provided with two diametrically opposed journals 6 integral with the wall of the crucible, for pivoting purposes.

A channel 7, which is placed externally along a generatrix, connects a hole 8 pierced at or near the base of the crucible to a pouring spout 9 in

50

2

order that only that part of the material which is free from floating impurities is poured out.

To prevent inclusion of the floating impurities when pouring out, a horizontal membrane 10 is provided.

I claim:

Electric crucible for heating materials so as to rapidly attain temperatures of 900° C. and above, having a cylindrical wall, inwardly projecting portions disposed along generatrices of said wall to penetrate into the material to be treated and thereby increase the surface of radiation and heat exchange towards the interior of the said crucible, each said projecting portion being hollowed axially from top to bottom to provide a cavity therein, and a heating element of corresponding shape arranged in each said cavity, a pouring spout on the outside of the upper part of the crucible integral with a vertical channel external of the wall, a hole pierced in said wall near its base in communication with said channel whereby only treated material from the lower part of the crucible and therefore free from all floating impurity can be poured from said spout, and a horizontal membrane at the upper part of the crucible to prevent passage of floating impurities towards the spout when the crucible is tilted to pour out the treated material.
